UNITED STATES PATENT OFFICE.

ISADORE SIMON, OF PHILADELPHIA, PENNSYLVANIA.

RADIATOR CORE.

Application filed November 8, 1923. Serial No. 673,606.

To all whom it may concern:

Be it known that I, ISADORE SIMON, a citizen of the United States, residing in Philadelphia, Pennsylvania, have invented 5 a Radiator Core, of which the following is a specification.

One object of this invention is to provide a radiator core, which in addition to being simple in construction and inexpensive to 10 make, shall be highly efficient as a heat exchanging device.

Another object of my invention is to provide a radiator core made of suitably connected sections comprising corrugated 15 lengths of metallic ribbon or other thin sheet material so formed as to produce a series of parallel air passages of equi-lateral triangular cross section, and narrow water passages made up of alternating horizontal and 20 inclined portions.

I also desire to provide a radiator core which shall include sheet metal lengths or strips of which certain are connected to form water and air passages and others of the 25 same outline are arranged as spacers which cooperate with the other strips to provide air passages of triangular cross section.

These objects and other advantageous 30 ends, I attain as hereinafter set forth, reference being had to the accompanying drawings, in which,

Fig. 1 is a front elevation of a portion of a radiator core constructed in accordance 35 with my invention;

Fig. 2 is a plan of the structure shown in Fig. 1;

Fig. 3 is a perspective view of a portion of one of the sheet metal strips of which my 40 radiator core is built up;

Fig. 4 is a front elevation of one of the sections of which the core is composed;

Fig. 5 is a front elevation of a portion of my radiator showing the spacer strips in 45 position therein;

Fig. 6 is an enlarged transverse vertical section of a portion of my radiator core taken on line 6—6, Fig. 2; and,

Fig. 7 is a modification of my invention 50 showing its spacer strips made with heat radiating tongues.

In carrying out my invention, I employ a suitable number of elongated metallic ribbons or thin strips of sheet metal such as 55 copper or brass, and by means of suitable rotary or reciprocating dies corrugate these strips so that they are serrated or zig-zag

in cross section as illustrated in Fig. 3. Each serration or corrugation consists primarily of two parts 1 and 2 bent to lie in planes defining an angle of 60°, with the 60 part 2 substantially double the width of that of the part 1. Thus each strip comprises a regularly arranged series of alternately arranged sections at angles of 60° to each other. While the two longitudinal 65 margins or edge portions of each part 1 and 2 of the strip are preferably flat as indicated at 3—4, the body or main portions of the strip intermediate said marginal portions are offset or depressed away from the 70 planes of said parts 3—4, as indicated at 5 and 6.

While the lines defining the junctions of the plane parts 3 or 4 with its adjacent plane 75 portions are straight and well defined, the portions 5 and 6 are gently merged or curved from one to the other, as indicated at 7 and 8 in Fig. 6, which illustrates a vertical cross section of one of the sections taken through its offset portion. Two strips are associated 80 together to form a unit structure having a series of rhomboidal cells. Preferably these two strips are formed integrally and when they are so formed a single long strip, corrugated as above described, is bent at its 85 middle portion through an angle of 180° and its two free ends are connected, say by seaming or soldering, as indicated at 9 in Figs. 4 and 5 to form one unit of my radiator. I then introduce between the two vertically elongated and substantially parallel 90 sides of the section, a spacer or filler strip made up of corrugations each having portions 1^a and 2^a at an angle of 60° to each other and like the main strip of which the completed section is formed, having the part 1^a approximately one-half the width of the part 2^a. In addition, said spacer strip has end portions 1^b parallel to the portions 2^a and having the width of the portions 1^a. 100 This spacer strip is preferably formed by the same dies or rolls as those forming the strip 1—2, with which, if desired, it may be identical in form. It will be noted that the filler strip is inverted or reversed with respect to the main strips of the unit. 105

A number of units, each made up with the spacer strip, as shown in Fig. 5, are now assembled side by side in a suitable clamping 110 device or holder so that the corrugations of one section set into or intermesh with the corrugations of adjacent units. Under these

conditions, the flat or plane portions 3—4 of any one unit lie in engagement and parallel with the similar flat portions of the two units on either side of it, to which they are 5 sweated or soldered by dipping in a bath of molten solder so that said units are continuously connected to each other along their longitudinal margins. The adjacent strips of each two adjacent units constitute a 10 pair of strips similarly positioned and identical in form.

Owing to the fact, that the portions 5 and 6 of the strips constituting each pair are offset or depressed, as above described and as 15 shown in Figs. 1, 5 and 6, there is formed between each pair a zig-zag water passage 10 of substantially uniform width from the top to the bottom of the core formed by the connected strips. Each of these passages is 20 made up of relatively short horizontal portions and portions inclined at an angle of 60° to the horizontal, of substantially twice the length of said first portions and each passage opens respectively at the top and the bottom. 25 The spacer strips 1^a—2^a of the above soldering operation, are rigidly connected by the solder to the sections between which they are mounted, and cooperate with the walls of 30 said sections to form air passages extending alternately transversely and in inclined lines through the radiator core.

The core thus formed possesses the advantage that its water channels are substantially uniform in cross section from top to bottom and by reason of the fact that they are made up of alternating horizontal and inclined portions, they retard the flow of water through them to an extent sufficient 35 to permit the conduction of the heat from the water to the metal walls of the radiator core in the most rapid and efficient manner. These walls with the intermediate spacer strips, provide a relatively extended surface 40 for transferring the heat of the water to the air flowing through the triangular air passages. Obviously the construction described is relatively inexpensive to make and assemble, especially in view of the fact 45 that the spacer strips may be of the same corrugated form and may be made, if desired, though not necessarily, by the same dies as those employed in making the main portions of the sections.

If desired, the spacers may have their 50 heat radiating surfaces materially increased by forming them with laterally projecting tongues, vanes or fins, such as those illustrated at 2^b in Fig. 7. These vanes assist in breaking up the air currents flowing 55 through the air passages.

I claim:

1. A radiator core comprising a plurality 60 of pairs of closely adjacent metallic strips similarly positioned and identical in form, each strip consisting of a regular repetitive

series of alternately arranged sections at angles of 60° to each other with alternate sections of each strip approximately one-half as long as the others, the last said sections of successive pairs of strips being 70 closely adjacent and in alignment with each other whereby rhomboidal cells are formed between adjacent pairs.

2. A radiator core comprising a plurality 75 of pairs of closely adjacent metallic strips similarly positioned and identical in form, each strip consisting of a regular repetitive series of alternately arranged sections at angles of 60° to each other with alternate sections of each strip approximately one-half as long as the others, the last said sections of successive pairs of strips being 80 closely adjacent and in alignment with each other whereby rhomboidal cells are formed between adjacent pairs, and means located in the several rhomboidal cells for dividing 85 each of them into smaller cells.

3. A radiator core comprising a plurality 90 of pairs of closely adjacent metallic strips similarly positioned and identical in form, each strip consisting of a regular repetitive series of alternately arranged sections at angles of 60° to each other with alternate sections of each strip approximately one-half as long as the others, the last said sections of successive pairs of strips being 95 closely adjacent and in alignment with each other whereby rhomboidal cells are formed between adjacent pairs, and means located in the several rhomboidal cells for dividing 100 each of them into four triangular cells.

4. A radiator core comprising in combination 105 a plurality of pairs of closely adjacent metallic strips similarly positioned and identical in form, each strip consisting of a regular repetitive series of alternately arranged sections at angles of 60° to each other and each alternate section of each strip being in alignment with the corresponding sections of the corresponding 110 strips of the other pairs, whereby rhomboidal cells are formed between adjacent pairs, and other strips identical in conformation with the strips of the said pairs 115 and located in inverted positions between the respective pairs, whereby each rhomboidal cell is divided into four equilateral triangular cells.

5. A radiator core made of a series of 120 sections each consisting of a length of sheet metal bent to form a series of rhomboidal cells, the marginal portions of the sections being connected and their main portions being offset to form water passages between 125 pairs of adjacent sections; with corrugated spacer strips in each section dividing the rhomboidal cells into cells of triangular section; and the walls of said latter sections having bent out tongues to facilitate the 130 radiation of the heat thereof.

6. A radiator core made of a series of sections each consisting of a length of sheet metal bent to form a series of rhomboidal cells, the marginal portions of the sections being connected and their main portions being offset to form water passages between pairs of adjacent sections; with a corrugated spacer strip in each section dividing the rhomboidal cells into cells of triangular section, said water passages each being made up of horizontally extending portions alternated with portions at an angle of 60° to said horizontal portion, the inclined walls of the corrugated strips having tongues bent out to increase the heat radiating surface.
7. A unit structure for a radiator core, comprising two metallic strips similarly positioned and identical in form, each strip consisting of a regular repetitive series of alternately arranged sections at angles of 60° to each other with alternate sections of each strip approximately as long as the others, whereby rhomboidal cells are formed between the two strips, and the last said alternate sections of the one strip respectively being slightly out of alignment with the corresponding sections of the other strip.
8. A unit structure for a radiator core, comprising two metallic strips similarly positioned and identical in form, each strip
- consisting of a regular repetitive series of alternately arranged sections at angles of 60° to each other with alternate sections of each strip approximately as long as the others, whereby rhomboidal cells are formed between the two strips, and the last said alternate sections of the one strip respectively being slightly out of alignment with the corresponding sections of the other strip, and means located in the several rhomboidal cells for dividing each of them into smaller cells.
9. A unit structure for a radiator core, comprising two metallic strips similarly positioned and identical in form, each strip consisting of a regular repetitive series of alternately arranged sections at angles of 60° to each other with alternate sections of each strip approximately as long as the others, whereby rhomboidal cells are formed between the two strips, and the last said alternate sections of the one strip respectively being slightly out of alignment with the corresponding sections of the other strip, and a third strip identical in conformation with the first said strips and located in inverted position between them whereby each rhomboidal cell is divided into four equilateral triangular cells.

ISADORE SIMON.
